To all whom it may concern:

Be it known that I, William J. Lundy, a citizen of the United States and residing at Olean, in the county of Cattaraugus and State of New York, U. S. A., have invented a new, original, and ornamental Design for a Jelly Tumbler, of which the following is a specification, reference being had to the accompanying drawing, forming a part thereof, wherein:

Figure 2 is a bottom plan view of a jelly tumbler embodying my new design.

I claim:

The ornamental design for a jelly tumbler, as shown.

WILLIAM J. LUNDY.
